UNITED STATES PATENT OFFICE.

GÜNTHER KEITEL, OF NEW YORK, N. Y.

BRASSIÈRE.

1,082,085.

Specification of Letters Patent. Patented Dec. 23, 1913.

Application filed June 16, 1913. Serial No. 774,016.

To all whom it may concern:

Be it known that I, GÜNTHER KEITEL, a citizen of the United States, and a resident of New York city, in the county of New York and State of New York, have invented certain new and useful Improvements in Brassières, of which the following is a specification.

This invention relates to a form of women's waist garment generally known as a brassière, whose function is to support the breasts of the wearer.

The object of this invention is to provide such a garment that will permit the easy insertion of stiffening members at the breast portions, that will be retained in position without the use of any form of fastening means, so that they can be removed when it is desired to laundry the garment, and as easily replaced, or others substituted.

In the accompanying drawing illustrating one embodiment of my invention:—Figure 1 is a front view of the garment. Fig. 2 shows the inner face of one front portion. Fig. 3 is a section on the line 3—3 of Fig. 1, and Figs. 4 and 5 show forms of stiffeners.

In the drawing a waist garment of the type known as a brassière is shown, comprising a rear part *a*, and a front part divided into two portions *b* and *c*, that are provided with suitable fastening means to secure them together on the person; the garment also having the usual arm holes *d* and *e*. It is usually made of muslin or similar light weight fabric.

At each of the breast portions is provided an inclosure or pocket, as indicated generally by the broken circular lines *f* and *g* in Fig. 1; at which places the fabric of the garment is of double thickness; and by sewing the layers together at such lines a round inclosure or pocket is provided. In each of these inclosures or pockets is contained a member *h*, formed of a light weight material that is comparatively stiff, and which is dished or shaped convex, of a curvature such as indicated in the sectional view of Fig. 3, to conform to the general shape of the breasts, and to present a neat and rounded appearance. These stiffening members may be provided with small holes *j*, for ventilation, so as to be cool to the wearer; and may also have a central opening *k*, to prevent undue pressure at that part of the

breast. Also, holes *m* may be formed in the margins to enable the stiffeners to be stitched in position when desired.

To facilitate easy and rapid removal of the stiffening members *h*, a pocket is shown on each side part *b* and *c*, of substantially circular shape, composed on one face of two pieces of fabric *n* and *o*, whose free edges meet or overlap on a chord *p* of the circles *f* and *g*; these two pieces being secured to the garment by sewing on the circles *f* and *g*; preferably on the inner face of the garment, so that the openings for the pockets are on the inside of the garment, as shown in Fig. 2. A round pocket is thus provided at each breast portion of the garment, into each of which one of the stiffening members *h* is inserted with the convex side outward; that will be securely retained in such position, and will be entirely inclosed in the garment. When it is desired to laundry the garment, these members *h* can be easily removed through the pocket at the chord or line *p*; and as easily replaced in the pockets. These stiffening members *h* may be formed out of any suitable material that is comparatively stiff. I have found that a stiff heavy form of an open mesh fabric known as buckram is well adapted for these stiffeners, as shown in Fig. 4; as it is of light weight, and the openings between the weft and warp provide excellent ventilation. Or a stiffening material of felt, or celluloid, or the like can be employed, as indicated in Fig. 5.

Having thus described my invention, what I claim is:—

A waist garment provided at each of the breast portions with a pocket that has one face formed of two substantially semi-circular complementary pieces which are secured to the garment by their curved margins only to form a substantially circular pocket, the straight margins of the pieces being free and substantially coincident, and circular stiffening members of concavo convex form one removably inserted in each said pocket at said free margins and the stiffening members being retained in position on the garment solely by the members forming the pockets.

GÜNTHER KEITEL.
